UNITED STATES PATENT OFFICE.

HENRY H. HOLTAN, OF CERROGORDO, MINNESOTA.

EGG-CANDLER.

SPECIFICATION forming part of Letters Patent No. 700,048, dated May 13, 1902.

Application filed January 7, 1902. Serial No. 88,805. (No model.)

To all whom it may concern:

Be it known that I, HENRY H. HOLTAN, a citizen of the United States, residing at Cerrogordo, in the county of Lac qui Parle and

5 State of Minnesota, have invented new and useful Improvements in Egg-Candlers, of which the following is a specification.

My invention relates to egg-candlers; and the object of the same is to construct a device 10 of this description by means of which six eggs can be placed in a row and candled simultaneously and the angle of the light varied at pleasure. The reason that it is constructed for six eggs is that this is the largest number 15 which can be safely handled at once, using both hands.

The novel construction designed by me for carrying out my invention is fully described in this specification and claimed and illustrated in the accompanying drawings, forming a part thereof, in which—

Figure 1 is a perspective of my device. Fig. 2 is a vertical longitudinal section of the same.

25 Like numerals of reference designate like parts in the different views of the drawings.

The numeral 1 designates the front of the casing of my candler, having a back 2 parallel to the front thereof and two diverging 30 sides 3. The casing is open at the bottom, but closed at the top by a cover 4. The casing is divided into two compartments 5 and 6 by a backwardly-inclined partition 7. The front 8 of the upper compartment 6 is open,

35 and a shelf 9 for supporting eggs is secured by means of a flexible connection 9^a just below the opening 8. A wire screen 10 is stretched over the opening 8 and is secured at the edges to the shelf 9 and to the cover 4

40 of the casing by hinges 10^b of flexible material, such as leather; but any other form of hinge may be employed. The screen 10 is curved to form a concave surface for the eggs to rest on. Strips 11 of padding are secured

45 to the edges of the screen to prevent injury resulting to the eggs.

The above combination of hinged shelf and screen forms a hood which can be adjusted up and down to vary the angle of incidence 50 of the light. Levers 12, fulcrumed on pivots

12^a, mounted in the sides of the casing, are located with their short arms engaging the shelf 9. By this arrangement the shelf can be adjusted by operating the lever 12.

The cover 4 is pierced by an aperture 14 to 55 accommodate a chimney 15 to carry off the heat of a lamp 16 for illuminating the eggs. The lamp 16 is located in the lower compartment 6 and extends through an aperture 17 in the partition 7. A reflector 18 is secured 60 to the back 2 just back of the lamp-flame and serves to concentrate the light upon the screen 10.

In operation the eggs are grasped three in each hand and placed on the screen 10. The 65 screen is then adjusted by means of the levers 12 till the rays of light strike the eggs at the proper angle. After the condition of the eggs has been ascertained they are removed and six more placed on the screen.

70 I do not wish to be limited as to details of construction, as these may be modified in many particulars without departing from the spirit of my invention.

Having described my invention, what I 75 claim as new, and wish to secure by Letters Patent, is—

1. In a device of the class described the combination with a casing constructed to accommodate a lamp, a shelf hinged to said casing, a concave screen secured to said shelf and a reflector mounted to concentrate the light of said lamp on eggs placed on said screen, substantially as described.

2. In a device of the class described, the 85 combination with a casing having diverging sides and divided into upper and lower compartments by a transverse partition, a hinged shelf located below an aperture communicating with said upper compartment, a concave 80 screen secured to said shelf, and a reflector mounted to reflect the light of a lamp placed in said casing against eggs placed on said screen, substantially as described.

3. In a device of the class described, the 95 combination with a casing having diverging sides and divided into upper and lower compartments by a transverse partition, a hinged shelf located just below an aperture in said upper compartment, a screen secured to said 90 screen, substantially as described.

shelf and constructed to support eggs, means for adjusting said hinged shelf to vary the angle of incidence of light falling on the eggs placed thereon, and a reflector mounted to reflect the light of a lamp placed within said casing on eggs placed on said shelf, substantially as described.

In testimony whereof I have hereunto set my hand in presence of two subscribing witnesses.

HENRY H. HOLTAN.
